UNITED STATES PATENT OFFICE.

PER OTTO PETTERSON, OF GALESBURG, ILLINOIS, ASSIGNOR OF ONE-HALF TO WILLIAM THOURREEN, OF GALESBURG, ILLINOIS.

WRENCH.

1,147,340.

Specification of Letters Patent. Patented July 20, 1915.

Application filed December 7, 1914. Serial No. 875,892.

To all whom it may concern:

Be it known that I, PER OTTO PETTERSON, a citizen of the United States, and a resident of Galesburg, in the county of Knox and State of Illinois, have invented a new and useful Wrench, of which the following is a specification.

My invention relates to that class of pivoted hand-grip wrenches which are provided with a removable head.

The principal object of the invention is to provide a wrench of the character recited which is adapted for use as a pipe-wrench, as a monkey-wrench, and as a general purpose wrench.

It is another object to simplify and generally improve the construction and to increase the capacity, utility and efficiency of wrenches of this type, without sacrificing any of their advantages.

Another object is to provide a spring, fixed in the channel of one of the handle members and adapted to tilt the shank out of the channel thereof, whereby it may be readily grasped in order to operate it.

Other objects relate to providing novel structural features and to novel combinations of elements.

Minor objects will presently appear; some of these will be obvious, while others will be specifically pointed out.

A preferred embodiment and a modification of the invention are illustrated in the accompanying drawings, in which the several elements and the constituent parts thereof are each designated by a distinguishing reference numeral, primes etc. being included in the modification to indicate parts corresponding to those in the principal views.

In said drawings: Figure 1 is a longitudinal section, partly in elevation, showing the invention embodied in the best form now known to me; Fig. 2, an elevation, partly in section and partly broken away, of the same structure shown in Fig. 1, but the parts in different relative positions from those there shown and the spring 28 omitted; Fig. 3, a modification, an elevation, partly broken away; and Fig. 4, a detail of parts shown in Fig. 3 but shown as in different relative positions.

Coming now to a detailed description of said drawings, 2 indicates a relatively stationary handle-member, U-shaped in cross section to provide a channel 2^a. On its back

it is provided with a pocket 3 having an aperture for a purpose presently described. Its rear end is preferably closed in the manner indicated at 4, and near its fore end it is provided with corresponding pairs of ears 5—5 and 6—6, these being in parallelism.

7 designates a normally bowed shank-releasing spring fixed at 8 to the element 2.

9 designates a pivoted, rotatable jaw, having preferably one toothed and three plane faces, all of which faces are operative. The character of these is of course optional and may be changed at will. 10 designates a suitable pivot, such as a bolt or a rivet by means of which the jaw 9 is mounted between the ears 5. It is to be noted that the serrated or toothed face of the jaw 9 is oblique to each of the others, and that there is preferably a slight clearance between the jaw and the shank, presently described, to provide for extreme freedom of movement of the latter.

11 designates a jaw or head, its operative face provided with teeth. 12 designates a shank, cast or forged integral therewith and provided on its back edge with rack-teeth 13. This member 11—12 I shall for the purposes hereof term a jaw-headed shank.

14 designates a scale.

15 designates the pivoted relatively movable member of the handle. It is preferably U-shaped in cross section except at its ends, the rear one of which is closed after the fashion shown at 16 and the forward one of which is provided with a cam-face 17 and a plane face 18. A pivot pin 19 or the like extends through the fore end of the member 15 and through registering apertures in the ears 6. The object of making the member 15 U-shaped in cross section is twofold; the surface presented to the operator's hand is circular or arciform, and the sides or cheeks provide a keeper for the shank 12.

20 indicates a stationary rack having a stud 21 projecting through the aperture (hereinafter referred to) in the pocket 3, its toothed face 30 presented to the rack 13.

28 indicates a curved spring, one of its end portions secured preferably to one of the ears 5 and its other end portion bearing against the adjacent face of the jaw 9.

In the structure shown in Fig. 3 the element 2' is like the element 2 shown in the principal figure except that it has no pocket

3. The elements 9', 10', 11' and 12' are substantially identical with the elements 9, 10, 11 and 12.

15' designates the pivoted handle member, its fore end pivoted at 19' between the ears 6' and provided with a cam face 17' and a tripping face 23.

24 indicates a locking dog pivoted at 25 between the ears 6' and provided with a 17 rack-face 26 which is presented to the rack-face 13' of the shank 12' and which in this construction is arranged on the front edge thereof. The trip end of the dog is indicated by 27.

15 28' indicates a jaw-inclining spring secured at 29' to one of the ears 5'.

I shall first describe the operation of the structure shown in Figs. 1 and 2. Assume the parts to be in the relative positions 20 shown in Fig. 2. In this position the spring 7 has expanded to its normal position (after the user has freed the handle member 15) and thus freed the teeth 13 from the teeth 30. Simultaneously it has tilted the rear 25 portion of the jaw-headed shank 11-12 to the inclined position shown. In this position the plane face 18 of the gripping-handle head will rest securely thereon and have no tendency to fly about. The teeth of the 30 head 11 will be inclined from the axial plane of the element 2. Also, the jaw 9 will be inclined in the opposite direction. The element 11-12 being freely slideable in the channel 2^a its head may be brought firmly 35 against a nut, pipe, bolt or other object against which the jaw 9 has already been placed, whereupon the handle member 15 is brought down to the position shown in Fig. 1, wherein the cam 17 has borne upon the 40 shank 12 to throw the rack teeth of the latter into engagement with the rack teeth 30. The element 11-12 is thus immovable relatively to any other one, and the article 45 grasped is held with extreme security. Release may be made merely by the operator releasing his grip, whereupon the spring 7 will act on the shank 12 and thereby the handle member 15 to free both. It will be clear that when the element 11-12 is with- 50 drawn from its channel, or removed, the jaw 9 may be rotated to bring into operative position either of its faces, and when so withdrawn said element 11-12 may be used as a hammer.

55 To operate the modified construction shown in Figs. 3 and 4 the user will raise the free or rear end 16' of the handle member 15' which, rocking on its fulcrum 19' will throw its fore end 23 down onto the trip end 60 of the dog 24, and as the latter rocks on its fulcrum 25 its toothed portion or rack 26 will be freed from the rack 13', whereupon, there being nothing to bind or frictionally contact the shank 12' it may be adjusted 65 freely in its channel in the U-shaped ele-

ment 2'. After the object operated upon has been grasped between the jaws 9' and 12', in the same manner as hereinbefore described, the operator will force the handle member 15' to the closed position shown in Fig. 3, 70 thereby forcing the cam face 17' against the heel portion of the dog 24 and the teeth 26 into engagement with those on the shank 12 to lock the jaws firmly on the held object. The spring 28' contacts the jaw 9' below the 75 pivotal point of the latter and will therefore tilt the jaw into the position shown in Fig. 3, or backward, which position is most desirable for grasping pipes, bolts, and other objects circular in cross section. 80

The wrench may be manipulated with extreme ease and facility; it may be used as a pipe, bolt, or monkey wrench; it is durable and strong; any of its parts or elements which become broken or inoperative may be 85 readily replaced; it is relatively light in weight and convenient to handle; there are no bothersome projections from its sides to strike other objects and prevent a long rotary stroke or a continuity of such; there are 90 no threads to strip, wear or slip; it may be preadjusted by means of the scale; it is economic of manufacture, and when the element 11-12 is extended, a correspondingly 95 longer handle and greater leverage results. 95

It has not been thought best to encumber this specification and the accompanying drawings with descriptions and illustrations of additional modifications which are neither 100 essential to nor form any part of the invention. In fact, it is apparent without such that numerous changes may be made in the details of construction, by modifications involving merely mechanical skill, without departing from the spirit and scope of the 105 invention, viewed in its broadest aspect. All this will be indicated in the claim hereof, wherein the omission of an element or the non-inclusion of reference to the detail features of the elements recited is intended to be a formal declaration of the fact that the omitted elements or features are not essential 110 to the invention covered by that claim.

Therefore, without limiting myself to particularities except where such are distinctly indicated, I claim as new the following, to-wit:

In a wrench, in combination, a relatively stationary and a relatively movable handle member both of which are channeled, the channel of each confronting that of the other, the movable member having a cam-shaped end, means for pivoting said end between the cheeks of the other member, a rack-faced locking element fixed in the stationary member, a jaw-headed shank slidably and tiltably mounted in the stationary member and having a rack edge adapted to engage said locking element, a rotatable jaw pivoted between the cheeks of the stationary 120 125 130

member, said cam-face resting on the shank and adapted to force the rack-edge thereof into engagement with said locking element when the movable handle member is swung 5 open on its pivot, and a spring fixed in the channel of the stationary member and adapted to tilt the rear end of the shank out of the channel thereof, out of engagement with said locking element, and into position 10 to be easily grasped.

In testimony that I claim the foregoing as my sole invention I hereto affix my signature, at Galesburg, in the county of Knox and State of Illinois, this 23rd day of November, 1914, in presence of two subscribing 15 witnesses.

PER OTTO PETTERSON.
